DESIGN FOR A DRAGLINE BUCKET

Joseph W. Hendrix, Shreveport, La.

Application May 1, 1940, Serial No. 92,078

Term of patent 14 years

To all whom it may concern:

Be it known that I, Joseph W. Hendrix, a citizen of the United States, residing at Shreveport, in the county of Caddo and State of Louisiana, have invented a new, original, and ornamental Design for a Dragline Bucket, of which the following is a specification, reference being had to the accompanying drawing, forming part thereof.

Figure 1 is a top plan view of a dragline bucket, showing my new design.

Figure 2 is a side elevational view.

Figure 3 is an end elevational view looking from left to right in Figure 1.

I claim:

The ornamental design for a dragline bucket, as shown.

JOSEPH W. HENDRIX.
